UNITED STATES PATENT OFFICE

CHARLES C. MEUTSCH, OF BUFFALO, NEW YORK

SPRING SUSPENSION FOR CHAIRS

Application filed March 13, 1931. Serial No. 522,264.

This invention relates to a cushion or spring suspension for chairs, davenport's and the like and relates more particularly to a type of furniture spring suspension in which 5 helical cushion springs are employed to support a person's weight and are mounted upon a sub or movable frame, which latter is resiliently connected by a plurality of sub-springs to the main frame of the chair (or 10 other article of furniture). By such a construction the weight of the person is sustained by two sets of springs that are in series with each other.

One of the objects of the invention is to 15 provide a spring suspension which is sufficiently "soft" to enable the same to be considerably flexed by very light pressures, but which, nevertheless, is so constructed as to also be resilient and to not strike bottom 20 when subjected to very heavy pressures.

Another object of the invention is to permit of easy replacement of the sub-springs (which take care of the very heavy pressures) so that, either at the time of purchase 25 of the chair (or other piece of furniture) or at any time thereafter, the person using the chair may readily have such sub-springs installed as most comfortably and adequately support his individual weight, and thereby 30 also permitting of readily replacing such springs as may in time become broken or weakened.

A still further object of the invention is 35 to provide such a construction of movable frame as will adequately prevent dust from rising up and collecting within the interior of the cushion and will, at the same time, not require, for the accomplishment of this end, being tacked to the entire periphery of the 40 main frame of the chair, as is now current practice.

A still further advantage of the invention 45 is to provide a suitable, spring-supported movable frame which will not cause any interference in the placing of the usual cords that tie the main or cushion springs together and keep the same in proper alignment.

A yet further object of the invention is to 50 provide a sub or movable spring suspension frame which is rendered adjustable so as to

enable the same to be applied to chairs of different sizes.

Numerous other objects of the invention and practical solutions thereof are disclosed in detail in the herein patent specification, 55 wherein:—

In the accompanying drawings,

Figure 1 is a horizontal section taken on line 1—1, Fig. 2, through a typical chair and illustrating, in fragmentary top plan, a 60 spring cushion or suspension with its cover removed.

Figure 2 is a vertical, transverse section through said chair taken on line 2—2, Fig. 1.

Figure 3 is a vertical, longitudinal section 65 through said chair, taken on line 3—3, Fig. 1.

Figure 4 is an enlarged, fragmentary, vertical, transverse section through said chair taken on line 4—4, Figs. 1 and 5.

Figure 5 is an enlarged, fragmentary top 70 plan of the parts shown in Fig. 4.

Figure 6 is an enlarged top plan of one of the sheet metal brackets, showing the same detached.

Figure 7 is an enlarged, vertical, transverse section through the lower part of one 75 of the cushion springs taken on line 7—7, Fig. 1.

Figure 8 is an enlarged, vertical section 80 similar to Fig. 7 but showing a modified method of securing the lower end of one of the said cushion springs to the movable frame.

Figure 9 is a horizontal section similar to Fig. 1 but showing a form of movable frame 85 which is adjustable to furniture frames of different sizes.

Figure 10 is a vertical, transverse section thereof taken on line 10—10, Fig. 9.

Similar characters of reference indicate 90 like parts in the several figures of the drawings.

My invention may be embodied in various forms and in furniture spring suspensions of various constructions, and the present applications are therefore to be regarded merely as some of the possible organizations which come within the scope of my invention and satisfactorily carry out the function of same in practice. As here shown, and referring 95 100

for the present to Figs. 1-7 inclusive, the same is constructed as follows:

It will be assumed for purposes of illustration that the invention is to be applied to an ordinary stiff, four-legged chair. The main frame A of such a chair comprises the vertical rear legs 10-10, which are joined together by the horizontal, transverse, rear frame bar 11;—the vertical front legs 12-12 which are joined together by the horizontal, transverse, front frame bar 13;—and the horizontal, longitudinal, side frame bars 14 and 15 which connect the front and rear sets of chair legs.

Secured by flat-head, countersunk wood screws 16 or otherwise to the upper flat faces of the several frame bars 11, 13, 14 and 15 are a plurality of appropriately spaced sheet metal brackets 17 whose inner ends or heads 18 are rounded and extend inwardly beyond the inner faces of said frame bars (see Figs. 4 and 5) and are preferably bent upwardly at a relatively small angle as shown. Each of said inner ends or heads 18 is provided with a slot 20 extending radially inward from its periphery and terminating in an enlargement or retaining hole 21. This slot may be omitted, if desired, as will be more evident from the subsequent description, its purpose being merely to facilitate the assembly of the cooperating parts. Formed on the upper face of each bracket head 18 is a locating groove or notch 22 which is substantially horizontal and is disposed perpendicularly of its companion frame bar and extends from the retaining hole 21 out to the periphery of said head 18. This notch, like the slot 20, may, if desired, be omitted, but constitutes the preferred construction of the invention for reasons which will hereinafter be more apparent.

Each bracket 17 is provided with a depending, tension, sub-spring 23, the upper and lower ends of which are curled in a longitudinal plane to form upper and lower securing loops or eyes 24 and 25. The upper eye 24 of each of said sub springs is detachably connected to its companion bracket 17 by being passed radially through the slot 20 of said companion bracket 17 and into the retaining hole 21 thereof and then placed in position in its companion locating notch 22.

Arranged within the geometric opening of the main frame A formed by the frame bars 11, 13, 14 and 16 is a movable frame B constituted chiefly of longitudinal and transverse bar metal ribs 26 and 27, the outer ends of which are slightly bent up at 28 and are perforated at 30 to enable the same to be detachably connected with the lower eyes 25 of the sub-springs 23. Said movable frame B is thus resiliently connected to the main frame A of the chair through the intermediary of the tension sub-springs 23. It will be noted that these sub-springs 23 are disposed sub-

stantially vertical and hence are not called upon to contribute to the rigidity of the movable frame itself, as could be the case if said movable frame were more or less flexible, and if these sub-springs were disposed at an angle to the vertical so as to be able to stiffen said flexible frame. In the present construction this movable frame B is so constructed as to be inherently stiff and rigid and constructed to derive its inherent strength entirely from the inherent stiffness of its bar metal ribs 26 and 27.

These metal ribs are covered on their upper surface with an upper sheet of fabric 31, and are separated from each other by a lower sheet of fabric 32. Said two sheets of fabric are longitudinally sewed with heavy thread or stitched together at 33 to form suitable, longitudinal, tubular enclosures 34 which snugly receive the longitudinal ribs 26 throughout the entire length of the latter, which are thus entirely encased in fabric. The transverse ribs 27 are, however, not entirely encased,—only their extreme ends being arranged within the short, transverse, tubular enclosures 35 which are formed by the short lengths of stitching 36. By this construction, these transverse ribs 27 are caused to be not only maintained in their proper location relatively to the two layers of fabric 31 and 32 (and hence to the movable frame B as a whole) but at the same time are covered by the upper fabric 31 and are separated from the longitudinal ribs 26 by the lower fabric 32. This separation of the two sets of metal ribs 26 and 27 from each other by said lower fabric 32 prevents said metal ribs from striking against each other with a metal-to-metal impact, thereby preventing the disagreeable metallic noises which would otherwise occur every time the person occupying the chair shifted his position.

The overall dimensions of the layers of fabric 31 and 32 are considerably larger than the overall dimensions of the opening in the main frame A. This permits the outer edges of said fabric to be turned up at 37 against the vertical inner faces of the frame bars 11, 13, 14 and 16 so as to form a dust tight joint between the movable frame B and the main frame A. This turned-up portion 37 is held up in position and prevented from sagging out of place by reason of the fact that both the stitching 33 and 36 extend clear out to the periphery of the fabric sheets 31 and 32, and thereby the tubular enclosures 34 and 35 are also carried out to said peripheral edge. Said tubular enclosures are thereby caused to extend out beyond the ends of their companion bar metal ribs 26 and 27 and to encase the lower part of the sub-springs 23, which latter, being mechanically forced to maintain an upright position, likewise cause the turned-up portions 37 to be held up in posi-

tion and thus prevented from sagging. The tendency of said fabric to sag at the corners is prevented by a relatively small number of sustaining tacks 38, as best shown in Fig. 1.

5 Arranged coaxially above the intersection of the bar metal ribs 26 and 27 and resting upon the movable frame B, taken as a whole, are a plurality of central cushion springs 40 which are preferably of the hour-glass or double conical shape, as is usual practice in spring constructions of this type. These central cushion springs do not rest directly upon said bar-metal ribs 26 and 27 but upon the upper layer of fabric 31 which covers the upper 10 faces of said ribs. Thus a metal-to-metal contact is avoided and, concomitantly, there results an elimination of any disagreeable noises which would otherwise occur to a greater or lesser extent every time the pressure carried upon any individual spring was 15 changed. In the construction shown in Figs. 1-7 inclusive these central cushion springs 40 are each held in place upon the movable frame B by two pairs of cotter pins 41 the 20 heads of which encircle the lowermost coil of their companion central cushion spring 40 and the shanks of which pass down through suitable holes in the movable frame B and are bent outwardly and clinched against the 25 lower face of said movable frame.

Arranged at the front part of the chair are a plurality of (three) front cushion springs 42 whose lower ends rest upon a suitable shelf 43 which is secured directly to and 30 forms a part of the main frame A. Said front cushion springs 42 are secured in place upon said shelf 43 by a plurality of U shaped brads or nails 39 in the usual and well known manner. It will be noticed, incidentally, that 35 said shelf 43 is suitably cut away at 44 to prevent interference with the front set of brackets 17.

The upper ends of all of said cushion springs 40 and 42 are laterally interconnected or tied together by a plurality of aligning cords 45 in the usual and well known manner. It is essential that some of these cords lie in vertical planes which intersect the axes of their companion ribs 26 and 27. 40 This involves securing said aligning cords 45 to the main frame A of the chair by means of cleat or anchoring tacks 46 which are disposed coaxially with respect to their companion brackets 17. To prevent interference 45 between said anchoring tacks 46 and said brackets 17, the latter are cut away at 47 so that said tacks may be driven into the main frame A of the chair through the central part of said cut-away portion 47.

50 In Fig. 8 is illustrated a modified method of securing the central cushion springs 40 to the movable frame B. In this construction instead of using cotter pins 41, the lower coils of said central cushion springs are not secured directly to the ribs 26 and 27 but to the

sheets of fabric 31 and 32, this being accomplished by suitable stitching 48.

In Figs. 9 and 10 is shown a modified form of movable frame B'. In this case each of the longitudinal, bar-metal ribs are constructed of two separate rib sections 261 of identical shape and each of the transverse ribs of two separate rib sections 271 of identical shape. Each of said rib sections is provided with a plurality of holes 50. Each pair of rib sections is held together by cotter pins 411 which pass through suitable sets of the holes 50 and are additionally employed to hold the lower coils of the central cushion springs 40 in proper position upon the sub or movable frame B'. In adapting this form of movable frame B' to any certain size of main frame A, each of the sets of rib sections 261 and 271 are suitably adjusted in length by moving the companion sections of each set 55 toward or from each other (as may be desired), after which the cushion springs 40 are placed in position and the cotter pins 411 passed down over the lower coil of their companion springs and through appropriate 60 holes 50 in their companion rib sections and clinched against the lower faces of the movable frame B'. It will be thus seen that these cotter pins 411 perform the dual function of holding the cushion springs 40 in place 65 upon the movable frame B' and also serve to hold together each companion set of rib sections in their proper linear relationship.

As a consequence of the novel construction of spring suspension hereinbefore described, the invention is seen to have the following specific novel features. For a relatively light load the central and front cushion springs 40 and 42 only are flexed, and, as these springs are relatively "soft", a considerable degree of flexure is obtained for a relatively light load. Such a spring suspension is, however, occasionally called upon to resiliently resist very heavy loads. When such a heavy load is applied, the sub-springs 100 23 come into play after a considerable stress has already been imposed upon the aforesaid cushion springs 40 and 42. It will be noticed that the sub-springs 23 have nothing to do with the rigidity or stiffness of the movable frame B or B'. Consequently, they are not under any flexure (as is current practice) unless an external load is actually being sustained by the spring suspension as a 105 whole. Thus they are enabled to function solely in the capacity of resiliently supporting the movable frame in a direction substantially parallel to the movement of said movable frame B or B', thereby providing greater resilience than would be possible if other 110 duties were also imposed upon them. The ribs 26 and 27 are separated from each other and from the cushion springs 40 and 42 by the sheets of fabric 31 and 32 so that any 115 noises due to metal-to-metal contact are eliminated.

inated. The use of the brackets 17 in no-wise interferes with the anchoring of the aligning cords 45 by the anchoring tacks 46. The joint between the movable frame B or 5 B' and the main frame A is rendered dust tight by the turned up edges 37 of the fabric 2, said edges being held in place by the sub-springs 23 which are encased in the extreme outer ends of the tubular enclosures 34 and 10 35. If said sub-springs 23 are too stiff or too soft for the purchaser or user, or if they should become broken, they can be very easily replaced by lifting the movable frame B or B' (as the case may be) and then pushing 15 the sub-spring 23 in question up and out of its companion locating notch 22 and then the upper spring eye 24 passed out through the slot 20 and the lower eye 25 of said spring unhooked from its companion rib 26 or 27 20 as the case happens to be. The new sub-spring is then placed in position by the reverse process. The lower ends of the central cushion springs 40 are definitely held in proper position on the movable frame B or 25 B' by either the cotter pins 41 or 411, or by the stitching 48. If the movable frame B' is to be adapted to main frames A of different sizes the form of the invention shown in Figs. 9 and 10 is used in which case the ribs may be 30 adjusted to any length desired by properly adjusting the pairs of rib sections 261 and 271 to the length desired and securing said adjustment and also locating the cushion springs 40 in place by means of the cotter pins 411.

I claim as my invention:

1. A furniture spring suspension comprising a main frame; a movable frame including only two plies of fabric stitched to form 40 primary and secondary tubular enclosures disposed perpendicularly to each other; ribs arranged perpendicularly to each other with-

in said tubular enclosures and separated from each other by the lower ply of said fabric; a cushion spring adapted to support a person's weight and resting upon said ribs and separated therefrom by the upper ply of said 70 fabric; and a resilient connection between said ribs and said main frame.

2. A furniture spring suspension comprising a main frame; a movable frame including plies of fabric stitched to form a tubular enclosure and turned up perpendicularly at its opposite edges; a rib arranged within the central part of said enclosure; a vertical cushion spring arranged upon said rib and helical springs arranged within the turned-up portions of the same tubular enclosure aforesaid and connected at opposite ends to said rib and to said main frame.

3. A furniture spring suspension comprising a main frame; a movable frame including a ply of fabric turned up perpendicularly at opposite edges, said turned up portions bearing against the inner face of said main frame; a rib secured to said fabric a vertical cushion spring arranged upon said rib; and a sub-spring connecting each end of said rib with said main frame and secured to said turned up portions of said fabric so as to hold the latter in place.

4. A furniture spring suspension comprising a main frame; a bracket secured thereto having a cut-away portion; a movable frame; a sub-spring connecting said movable frame with said bracket; a cushion spring arranged on said movable frame; and an aligning cord secured to said cushion spring and tacked to said main frame at the part thereof exposed by the cut-away portion of said bracket.

In testimony whereof I hereby affix my signature.

CHARLES C. MEUTSCH.
